UNITED STATES PATENT OFFICE.

ROBERT STEEL, OF PHILADELPHIA, PENNSYLVANIA.

WARDROBE-BEDSTEAD.

SPECIFICATION forming part of Letters Patent No. 375,391, dated December 27, 1887.

Application filed October 26, 1886. Serial No. 217,280. (No model.)

To all whom it may concern:

Be it known that I, ROBERT STEEL, a citizen of the United States, residing at Philadelphia, in the county of Philadelphia and State 5 of Pennsylvania, have invented certain new and useful Improvements in Wardrobe-Bedsteads, of which the following is a specification.

The invention has for its object the construction of a wardrobe-bedstead, in which the use of weights or springs to counterbalance the weight and leverage of the frame for containing the bedding and the connected foot-board with its legs are dispensed with; and it consists in the connection to the standing case of 15 a bedstead of a rectangular folding portion for containing the bedding, pivoted thereto by means of bearings upon a rod or shaft extending across the width of the folding portion 20 through its sides and the contiguous sides of the standing case, which is provided with a removable crank upon one exposed outer end and a drum central longitudinally, to which an end of a cord is permanently attached, and 25 which passes around and within the grooves of two pulleys arranged vertical with each other in mortises of said head-board over and diagonally downward to the free end of the bedding-frame, and connected to a hook on the 30 inner surface of said end, attachable thereto and detachable therefrom, whereby by winding the cord upon the drum by means of the crank the bedding-frame may be brought into a vertical parallel plane with the standing case or 35 lowered to a horizontal plane therewith by relaxation of the cord.

The invention further consists in connecting the foot-board and its legs to the standing case by means of lazy-tongs, in such a manner that 40 they may be closed against or extended outward horizontally from said head to form a support for the free end of the bedding-frame, and form therewith a complete bedstead for occupancy, as will be more fully understood 45 from the following description.

In the accompanying drawings, which make a part of this specification, Figure 1 is a front elevation of the bedstead in a closed position. Fig. 2 is a side elevation of same. Fig. 3 is 50 a plan view with the top of head-board removed, the folding portion drawn up, the foot-

board and lazy-tongs being extended. Fig. 4 is a plan view with the folding portion drawn down in a horizontal position. Fig. 5 is a side elevation, the folding portion in same position. Fig. 6 is a vertical longitudinal section in the 55 same position.

Like letters of reference in all the figures indicate the same parts.

A is the standing case, the lower end of 60 which is provided with feet that rest upon the floor.

B is the folding portion, which is connected and pivoted to said standing case by means of the shaft C, passing across the width of said 65 bedstead, uniting the parts together, and journaled in the sides a a' of said case and folding portion. This shaft has a drum, D, situated midway of its length, to which one end of the cord E is attached, and said cord then is passed 70 around the pulleys G G', located in mortises of the standing case over the same, and down diagonally across the length of the bedstead, where it is connected by means of a ring, I, to the hook H on the inner surface of the free 75 end of the bedding-frame B. A crank, J, upon an exposed outer end of the shaft C, that is removable, is provided for the purpose of rotating said shaft and winding the cord E upon the drum D, which gradually draws the folding 80 portion into a vertical position close upon and in a parallel plane with the standing case. A reverse motion of the crank causes a relaxation and unwinding of the cord, permitting the folding portion to assume its horizontal 85 position.

The foot-board K and its legs are connected to the standing case near its base by the horizontal lazy-tongs L, whereby said foot-board may be drawn apart from the standing case a 90 sufficient distance to act as a support for the free end of the folding portion, or closed against the head after the elevation of said folding portion.

By my construction the use of weights or 95 tensional springs to counterbalance the weight of the folding portion, to permit an easy elevation of same, are dispensed with.

The ring I may be detached from the hook H when the folding portion is in its horizontal position and the cord E wound around the drum D to elevate it out of the way.

I am aware that patents have been issued to G. L. Baar, No. 339,516, and to S. S. Burr, Reissue No. 10,225, each showing a cord passing over the pulley and having a weight upon the end of the cord. As such construction is not new, I therefore do not claim it as part of this invention.

I claim as my invention and desire to secure by Letters Patent—

10. 1. In a wardrobe-bedstead, the combination of the standing case A, folding portion B, pivoted thereto by means of the shaft C, having journals in said case and folding portion, and foot-board K, connected by means of lazy-tongs L to the standing case, whereby said foot-board may be moved in a horizontal parallel plane with the base upon the elevation

of the folding portion, substantially in the manner herein shown and described.

2. In a wardrobe-bedstead, the combination of the standing case A, having pulleys G G', located at top and bottom of same, folding portion B, provided with hook H, and connected to one end of the standing case by means of shaft C, which has a drum, D, cord E, attached to and passing around said drum over pulleys G G', and having ring I, said shaft being rotated by the crank for elevating and lowering the folding portion, substantially in the manner herein shown and described.

ROBERT STEEL.
